UNITED STATES PATENT OFFICE

NORMAN L. ROULET, OF TOLEDO, OHIO

DESIGN FOR A TROPHY PLAQUE

Application filed February 14, 1931. Serial No. 38,661. Term of patent 14 years.

To all whom it may concern:

Be it known that I, NORMAN L. ROULET, a citizen of the United States of America, residing at Toledo, Lucas County, Ohio, have invented a new, original, and ornamental Design for a Trophy Plaque, of which the following is a specification, reference being had to the accompanying drawings, forming part thereof.

I claim:

The ornamental design for a trophy plaque as shown.

NORMAN L. ROULET.
